TRAIN-CONTROL APPARATUS.

1,195,029.

Specification of Letters Patent. Patented Aug. 15, 1916.

Application filed April 14, 1915. Serial No. 21,307.

To all whom it may concern:

Be it known that we, RAYMOND M. KAUFMANN and THOMAS M. FREEBLE, both citizens of the United States, and residents, respectively, of Pittsburgh, Allegheny county, Pennsylvania, and Rochester, Beaver county, Pennsylvania, have invented a new and useful Train-Control Apparatus, of which the following is a full, clear, and exact description, reference being had to the accompanying drawings, forming part of this specification, in which—

Figure 1 is a sectional elevation, largely diagrammatic view of apparatus embodying our invention; Fig. 2 is a diagram showing an arrangement of track circuits; Figs. 3 and 4 are detail sectional views of two of the valves employed; Fig. 5 is a sectional view, largely diagrammatic, showing a modified form of apparatus; Fig. 6 is a detail sectional view of the rotary pressure-equalizing valve; and Fig. 7 is a detail sectional view of the rotary valve shown in Fig. 5.

Our invention has relation to train control apparatus, and is designed to provide means of simple, reliable and efficient character, whereby an engineer or motorman, under predetermined track conditions, will be compelled to reduce the speed of his train, or else be subject to an automatic stop. Our invention provides apparatus of this character in which the control of the train is left largely in the hands of the engineer or motorman, provided signals and orders are properly obeyed. If, however, such signals and orders are not obeyed, the control of the train is automatically taken from his hands and the train is brought to a stop.

Broadly considered, our invention comprises a speed-controlling device for the train, such as a brake valve; operating means for such device acted upon at all times by the speed of the train, and having its normal condition dependent upon the speed of the train; and supplementary speed-controlled mechanism, itself controlled by track conditions, and operating under predetermined track conditions to modify the normal operation of said means and effect the operation of the speed-controlling device.

Our invention will be best understood by

reference to the accompanying drawings in which we have shown a preferred embodiment together with a modification thereof, 55 and which will now be described, it being premised that the invention is subject to various modifications within the scope of the appended claims, and that the apparatus shown is illustrative only, the drawings being largely diagrammatic, and the parts being capable of various mechanical embodiments.

In these drawings, the numeral 2 designates an air-pipe extending to the main 65 reservoir of the air-brake system. This pipe leads into a pressure cylinder 3 having therein a flexible diaphragm 4, controlling, through the connections 5, a brake release valve 6. This release valve 6 controls a port 70 7 in the train air-pipe 8. When the valve 6 is open, air from the pipe 8 escapes through the port 7 into the space or chamber behind the diaphragm 4, and thence to the atmosphere through any suitable opening, such as 75 that shown at 9.

The numeral 10 designates a shaft mounted for rotation and also for endwise movement, which is constantly driven when the train or vehicle is in motion by suitable connection with one of the driving axles (not shown). This shaft will be referred to hereinafter as the speedometer shaft. One end portion of this shaft extends within one end portion of the cylinder 3 and carries in 85 said cylinder a piston 11. This piston is fixed to the shaft 10 to move endwise therewith, but the shaft is provided with suitable journal bearings in the piston, such as indicated at 12, so that the shaft may rotate 90 without turning the piston.

13 is a centrifuge member which is pivoted to the speedometer shaft at 14. This member is shown as being in the form of a ring lying in an oblique plane and having a 95 loose engagement at 15 with the slot of a fixed frame member 16 in which the shaft 10 is journaled.

17 is a coiled spring which acts upon the shaft 10 in opposition to the centrifuge. It 100 will be readily seen that as the speed of the shaft 10 increases, the centrifuge member will tend to assume a more nearly perpendicular position, and that in doing so it will

move the shaft 10 endwise against the action of the spring 17.

We will now describe the means by which the pressure in the cylinder 3 between the 5 piston 11 and the diaphragm 4 is controlled. The pipe 2 is provided with a valve chamber 18 having therein a control valve 19. This valve is shown as of the slide type, its stem being connected to a lever 20 having a 10 fixed pivot at 21 with its free end portion engaged with a grooved collar 22 on the speedometer shaft 10. 23 is another valve in the pipe line 2. This is shown as being of the rotary type (shown in detail in Fig. 15 4) and is designed to be opened by the de-energization of a magnet 24 through the connections 25. This magnet is controlled by any suitable arrangement of track apparatus. This does not form any part of the 20 present invention and may be of various characters and arrangements. In Fig. 2 we have, however, shown an arrangement of track circuits for controlling this magnet for the purpose of illustration only. In this 25 arrangement, the magnet 24 is included in a local circuit 26, including a battery 27, and a relay armature 28. The latter is controlled by a relay magnet 29, whose circuit is grounded at both sides on the frame of the 30 engine or vehicle indicated at 30, upon opposite sides of separating insulation 31. The connection at one side is made through an armature 32 of the relay 29. 33 designates track relays connected across the track 35 rails 34, and each having two armatures 35 and 36.

Without further describing in detail the 40 circuits shown, it will be apparent from Fig. 2 that so long as the magnet 29 remains energized, the magnet 24 will also remain energized, the latter being in a normally closed circuit completed through the armature of magnet 29. When a vehicle is 45 in a position relative to the end of one block and the entrance to another block, indicated in Fig. 2, the condition of the magnet 29 will depend upon the condition of the magnet 33 in the next succeeding block. If this magnet 33 has been deenergized, it 50 will be apparent that the magnet 29 is also deenergized; while if the magnet 33 remains energized, magnet 29 remains energized.

The pressure cylinder 3 is provided with a loaded escape valve 37, which may be set 55 to open at any desired pressure less than that at which the diaphragm 4 will operate to open the valve 6. This escape valve is located at an intermediate portion in the length of the cylinder 3 and the port 38 leading thereto will be open so long as the speed of the train is below a certain point. When, however, the speed of the train is increased beyond this point, the piston 11 will 60 be moved sufficiently to the right in Fig. 1,

to close the port and pressure will build up 65 in the cylinder 3, beyond the point at which the valve 37 is set to open. Inasmuch as this increased pressure in the cylinder 3 would tend to oppose the action of the centrifuge and thereby prevent said piston from 70 always being in a position corresponding exactly to the speed of the train, we provide the shaft 10 with another piston 39, in which said shaft can rotate (as in piston 11) and which works in a cylinder 40.

75 41 is a pipe connected with cylinder 40, behind the piston 39, and leading into a diaphragm chamber 41^a, below a diaphragm 41^b (Fig. 6) and 42 is another similar diaphragm chamber having a pipe connection 43 leading from below its diaphragm 42^a to the cylinder 3 in front of the piston 11.

44 is a rotary valve, shown between the two diaphragm chambers 41^a and 42. A 85 bar 44^a passes through this valve and is connected to the stems 44^b of the diaphragms. Pipe 41 has a branch 41^c, and this, in turn, has the two branches 41^d and 41^e leading 90 into the casing of the valve 44.

45 is a pipe leading from the pipe 2 or other source of supply into said valve casing. Valve 44 has the ports 44^c and 44^d.

95 So long as the pressure behind the piston 39 is equal to the pressure in the chamber 3, the valve 44 remains in the closed or inactive position shown in Fig. 6. As the pressure in the chamber 3 increases, the diaphragm 42^a rises, thereby turning the valve 44 until the port 44^c connects the 100 branch pipe 41^d with the pressure pipe 45. This admits pressure to the cylinder 40, until the pressures in 40 and 3 are equalized. This operation will be repeated as often as the pressure in 3 exceeds that in 40. Piston 105 39 is, therefore, acted upon at all times by a pressure equal to that opposing the piston 11; and as the two pistons are of equal areas, the effect upon the centrifuge of an increasing pressure in 3 is neutralized. If, on the other hand, the pressure in 40 is the greater, valve 44 is turned in the opposite direction to connect branch pipe 41^e with the atmosphere through port 44^d, and thus restore the equilibrium. The particular valve 115 mechanism just described is illustrative only, and may be widely varied in practice, as may also the equalizing device in general.

The numeral 47 designates an indicator having two pointers 48 and 49, arranged 120 to travel over a scale 50. The pointer 49 is operated by a pipe connection 51, leading to a small cylinder 52, which is secured in the front head of the cylinder 3. In this cylinder 52 is a piston 53, connected by a 125 rod 54 with the piston 11. The details of this indicator form no part of our invention, indicators of this general character

being well known in the arts. It will be apparent that as the piston 11 moves to the right, the piston 53 will be correspondingly moved, thereby creating a partial vacuum 5 in the pipe 51, the extent of this vacuum being proportional to the extent of movement of the piston 11, and therefore, proportional at all times to the actual speed of the train. The pointer 49 will, therefore, 10 at all times indicate the actual speed of the train. The pointer 48 is actuated by a pipe connection 55 with the air-pipe 2, the pointer being moved by the pressure in said pipe. This pointer 48, therefore, indicates 15 the permissive speed of the train, as will be hereinafter described.

The general operation of the invention as thus far described is as follows: Valve 23 is normally held closed by the action of the 20 magnet 24, so long as normal track conditions exist. When, however, the magnet 24 is deenergized, as, for instance, when the train receives a caution signal, the valve 23 is opened, thereby admitting air into the 25 valve chamber 19 from the pipe 2. The port 19^a controlled by the valve 19 is shown as being of narrow oblong form, and the extent of this port which is uncovered at any 30 particular time depends directly upon the actual speed of the train at that time, due to the connection of that valve to the lever 20, which is, in turn, connected with the speedometer shaft 10. As soon, therefore, as 35 the valve 23 is opened, air commences to flow into the cylinder 3. The time required after this operation before sufficient pressure is built up in said cylinder to actuate the diaphragm 4 to open the brake release valve 6 depends upon two factors, viz., first, 40 the position of the piston 11, which depends upon the speed of the train; and second, the extent and duration of the opening of the valve 19, which also depends upon the speed of the train. If the speed of the train at 45 this time is below the predetermined maximum, the escape port 38 will be uncovered and the train can proceed at about this speed, without the brakes being applied. If the speed is above the maximum, a comparatively short time will be required to open 50 the valve 6, as the port 38 will be covered and the valve 19 will be comparatively wide open. To avoid the application of the brakes, the engineer must at once reduce his 55 speed below this maximum. The pointer 49 shows the engineer his actual speed, and the pointer 48, whose position is dependent upon the degree of pressure in the cylinder 3, shows the engineer the permissive speed at 60 which he may continue to run without the brakes being applied. Independent of track conditions, if the speed of the train at any time exceeds a predetermined maximum under normal conditions, the piston 11 will

move to the right as the speed increases until the projection 11^a thereon will contact with the diaphragm 4 and open the release valve 6, and thus apply the brakes. This action is independent of pressures in the cylinder 3.

Although not essential to our invention, we prefer to provide means which will effect the automatic application of the brakes should any part of the apparatus get out of working condition. This part of our invention corresponds generally to the function of a normally closed circuit in electrically operated systems. It consists in maintaining in the pressure chamber of the cylinder 3 at all times a certain minimum 80 pressure, and in providing means whereby if this minimum pressure is not maintained, by reason of leakage, the brakes will be applied. Normally, this minimum pressure is insured by the operation of a diaphragm 85 valve 59 which is placed in a bypass 57 from the pipe 8 to the cylinder 3. The diaphragm is subjected at one side to the same pressure as that existing in the cylinder 3. If the pressure in cylinder 3 falls below the predetermined minimum, the diaphragm will 90 act to open the valve 59 and admit more air to said cylinder through the bypass 57. If for any reason the apparatus is not in proper working condition, and this minimum pressure is not maintained, the brakes will be applied by means of the continued 95 escape of pressure from the pipe 8 through the valve 59.

After having received a track indication, 100 it is frequently necessary for the train to back up within the block, and to keep the apparatus in normal working condition during this backward movement of the train, any pressure which has been built up in the 105 cylinder 3 should be reduced to an extent corresponding to the backward movement of the train. For this purpose, we provide the pipe 2 in advance of the valve 23 with a reverse valve 61 and connect the stem of this 110 valve, as indicated at 62, with the engineer's reverse valve lever (not shown). The valve 61 is normally in the position shown in Fig. 2, in which it has a port in line with the pipe 2. When the engineer's reverse lever is operated, this valve is turned so as to bring the branch port 61^a into registry with the pipe leading to the valve 23, and to bring the other branch of said port into register 115 with an escape pipe 63 having the escape valve 64, and also close entry of air into the pipe 2. Escape valve 64 is set to be opened by a pressure greater than the minimum allowed in cylinder 3, so as to keep pressure in cylinder 3 at its minimum. With the 120 valve 61 in this reversed position, air will pass backwardly through the valves 19 and 23 and will escape through the pipe 63 to an 125

extent determined by the speed of the backward movement and the distance traveled. When the train again starts forward, the proper conditions have thus been restored. 5 In this manner, when the train again starts forward, it will start with the same pressure condition in the cylinder 3, as if the train were initially starting from the point to which it was backed.

10 For the purpose of permitting escape of pressure from the cylinder 3 after normal track conditions have been restored and the valve 23 has been closed by the reenergizing of the magnet 24, the pipe 2 is provided with 15 the bypass pipe 65 leading around the valve 19 and into the casing of the valve 23. The valve 23 when closed has a port 66, which connects the pipe 65 with a branch pipe 67, leading to the escape pipe 63. This port is 20 closed when the valve 23 is opened so that no air can escape through it, except when said valve is closed.

In Fig. 5, we have illustrated a modification of our invention in which, instead of a centrifuge for controlling the position of the piston in the pressure chamber, we have shown such position as being controlled by air pressure and which pressure is, in turn, controlled by the speed of the train. In 30 this modification, the numeral 68 designates the pressure chamber having the piston 69, corresponding to the piston 11 of the form first described. 70 is the diaphragm which actuates the brake-applying valve 71. The 35 rod 72 of the piston 69 carries another piston 73 at its opposite end, working in a chamber 73^a, having a port 74, leading therein behind the piston 73. 75 is the admission pipe leading to the opposite end of the 40 chamber 68. The numeral 76 is a rotary valve for controlling the ports 74 and 75 and has its stem 77 geared to a moving part of the train, a portion of the gears being shown at 78. This valve has a plurality of 45 peripheral pockets 76^a which, as it is rotated, are successively filled with air from the main supply pipe (leading through the valve 81 hereinafter described) and discharge such air into the pipe 75. The valve 50 also has another series of pockets 76^b which, in a similar manner, transfer air to or from the pipe 74, from the supply connection 76^c. This valve corresponds to the valve 19 of the 55 form first described. 79 is a valve corresponding to the valve 23 of the form first described, and controlled by a magnet 80, corresponding to the magnet 24, and controlled by track conditions. 81 is a valve corresponding to the valve 61. 82 is a compensating or balancing cylinder and piston, acting upon the piston rod 72 for the same purpose as the cylinder 40 and piston 39 of the form first described. 82^a is the diaphragm and valve mechanism for equalizing 60 the pressures on the piston 69, and which is

similar to that before described. 83 is an indicator similar to the indicator 50 and actuated in a similar manner. Air is being constantly admitted into the chamber 73^a behind the piston 73 by the action of the pockets 76^b of the valve 76 until the pressure behind said piston equals the supply pressure (if the speed of the train be great enough) and said piston and the piston 69 are moved to the right a distance proportional to the 75 speed of the train. Normally, no air is being admitted to the cylinder 68; but when the magnet 80 is engaged to open the valve 79 to the position shown in Fig. 5, air will be admitted to such cylinder; and the pressure therein will be proportional to the speed of the train and the distance traveled by the train after magnet 80 is deenergized. It will be readily seen that the action of the apparatus shown in this modification is in 80 all respects similar to that first described, except that the piston 73, together with the means for admitting air pressure behind said piston, takes the place of the centrifuge member 18. It will be understood that the 90 position of the valve 76 is controlled by the speed of the train, the greater the speed the greater being the amount of air admitted behind the piston 73. 84 is a small escape opening for venting the air behind the piston 73.

In the embodiments of our invention which have been described, it will be noted that the air required for its operation is derived from a connection with the usual air 100 brake system. This permits the apparatus to be readily applied to existing brake systems and it is also capable of use in connection with existing track systems by slight modification. It may, however, derive pressure from any suitable source. By the use of the system, if an engineer fails to obey a caution signal and reduce speed within safe limits, the train will automatically be brought to a stop. By properly reducing 110 the speed, the train may be allowed to proceed under a safe speed until a further track indication is received.

It will be understood that the word "train" as used herein and in the appended 115 claims is designed to include either a number of vehicles or a single vehicle. It will also be understood that instead of a brake-applying valve, any other suitable speed-controlling means may be employed.

The present application is a continuation-in-part of our application Serial No. 852,207 filed July 21, 1914.

We claim:

1. Train control apparatus, comprising a 125 pressure chamber, means arranged to be operated by a predetermined pressure in said chamber to control the speed of the train, means normally controlled by the speed of the train and working in said chamber to 130

affect the pressure therein, and means for admitting pressure to said chamber controlled by track conditions and also by the speed of the train under such conditions, substantially as described.

2. Train control apparatus, comprising a pressure chamber, means operated by pressure in said chamber to control the speed of the train, a piston in said chamber, means for moving said piston in accordance with the actual speed of the train, and means operative under predetermined conditions and controlled by the speed of the train for admitting pressure to said chamber, substantially as described.

3. Train control apparatus, comprising a pressure chamber, means operated by pressure in said chamber to control the speed of the train, a piston in said chamber, means for moving said piston in accordance with the actual speed of the train, and means operative under predetermined conditions and controlled by the speed of the train for admitting pressure to said chamber, together with means for maintaining at all times a minimum pressure in said chamber, substantially as described.

4. Train control apparatus, comprising a pressure chamber, means operated by pressure in said chamber to control the speed of the train, a piston in said chamber, means for moving said piston in accordance with the actual speed of the train, and means operative under predetermined conditions and controlled by the speed of the train for admitting pressure to said chamber, and means for maintaining at all times a minimum pressure in said chamber, together with means for effecting the automatic operation of the speed control device if the pressure in said chamber falls below such minimum, substantially as described.

5. Train control apparatus, comprising a pressure chamber, means operated by pressure in said chamber to control the speed of the train, a piston in said chamber, means for moving said piston in accordance with the actual speed of the train, and means operative under predetermined conditions and controlled by the speed of the train for admitting pressure to said chamber, together with means for properly decreasing the pressure in said chamber upon backward movement of the train, substantially as described.

6. Train control apparatus, comprising a pressure chamber, means operated by pressure in said chamber to control the speed of the train, a piston in said chamber, means for moving said piston in accordance with the actual speed of the train, and means operative under predetermined conditions and controlled by the speed of the train for admitting pressure to said chamber, together with means for indicating the actual speed of the train and the permissive speed

of the train and pressure connections with the apparatus for operating the indicating means, substantially as described.

7. Train control apparatus, comprising a pressure chamber, means arranged to be operated by increase of pressure in said chamber for controlling the speed of the train, a piston in said chamber, an escape from said chamber arranged to be closed by the piston at an intermediate point of its movement in the chamber, train-actuated means for moving said piston in accordance with the speed of the train, and valve mechanism for admitting pressure to said chamber under predetermined conditions, said valve being controlled in part by track conditions and in part by the speed of the train, substantially as described.

8. Train control apparatus, comprising a pressure chamber, means operated by change of pressure in said chamber to control the speed of the train, a piston in said chamber, a train-driven member arranged to move the piston in accordance with the speed of the train, and means for compensating the effect of change of pressures in said chamber upon the movement of said piston, substantially as described.

9. Train control apparatus, comprising a pressure chamber, means operated by change of pressure in said chamber to control the speed of the train, a piston in said chamber, a train-driven member arranged to move the piston in accordance with the speed of the train, and means for compensating for change of pressures in said chamber upon the movement of said piston, said means comprising an auxiliary piston and cylinder arranged to act upon the piston in opposition to the pressure in said chamber, substantially as described.

10. Train control apparatus, comprising a pressure chamber, means arranged to be operated by change of pressure in said chamber to control the speed of the train, a piston in said chamber, an endwise movable shaft arranged to move the piston in the chamber, a centrifuge which effects an endwise movement of the shaft proportional to the speed of the train, and valve mechanism for controlling the pressure in said chamber, said valve mechanism being controlled in part by track conditions and in part by the speed of the train, substantially as described.

11. Train control apparatus, comprising a pressure chamber, means operated by change of pressure in said chamber for controlling the speed of the train, train-actuated means for effecting a movement of the piston in the chamber in proportion to the actual speed of the train, a passage for admitting pressure to said chamber, a valve controlling said passage and itself controlled by track conditions, and another

valve also controlling said passage and itself controlled by the speed of the train, substantially as described.

12. Train control apparatus, comprising
5 a pressure chamber, means operated by change of pressure in said chamber for controlling the speed of the train, train-actuated means for effecting a movement of the piston in the chamber in proportion
10 to the actual speed of the train, a passage for admitting pressure to said chamber, a valve controlling said passage and itself controlled by track conditions, and another valve also controlling said passage and itself
15 controlled by the speed of the train, together with means for effecting an automatic operation of the speed-controlling means when the pressure in the chamber becomes less than a predetermined minimum,
20 substantially as described.

13. Train control apparatus, comprising a pressure chamber, means operated by change of pressure in said chamber for controlling the speed of the train, train-actuated means for effecting a movement of the piston in the chamber in proportion to the actual speed of the train, a passage for admitting pressure to said chamber, a valve controlling said passage and itself controlled by track conditions, and another valve also controlling said passage and itself controlled by the speed of the train, together with means for permitting the escape of pressure from said chamber after
30 operation of the said valves and when normal track conditions are restored, substantially as described.

14. Train control apparatus, comprising a pressure chamber, means operated by change of pressure in said chamber for controlling the speed of the train, train-actuated means for effecting a movement of the piston in the chamber in proportion to the actual speed of the train, a passage for admitting pressure to said chamber, a valve controlling said passage and itself controlled by track conditions, and another valve also controlling said passage and itself controlled by the speed of the train, together with means for permitting escape of pressure from said chamber after operation of said valves and during reverse movement of the train, substantially as described.

15. Train control apparatus, comprising a pressure chamber, means operated by pressure in said chamber to affect the speed of the train, a piston in said chamber, a train-driven shaft connected to the piston to move it endwise in said chamber, a centrifuge carried by said shaft to effect an endwise movement thereof and of the piston in proportion to the speed of the train, a pressure supply passage leading into said chamber, a valve controlling said passage and having an actuating connection with said shaft, and an-

other valve also controlling said passage and controlled by track conditions, substantially as described.

16. In train control apparatus, an air chamber, a piston movable therein, a speed-controlled shaft for moving the piston, means controlled by the movement of the train under predetermined conditions for modifying the action of said piston, and speed-controlling means arranged to be operated by said piston when the speed of the train exceeds a predetermined maximum, substantially as described.

17. Train control apparatus, comprising a pressure chamber, means controlled by said chamber for affecting the speed of the train, a piston in said chamber, a source of pressure supply for the chamber, a speed indicator connected to the pressure chamber to indicate the permissive speed of the train, and another speed indicator connected to said piston and operating to indicate the actual speed of the train, substantially as described.

18. Train control apparatus, comprising an air chamber, a piston in said chamber, a speed-controlled device for actuating said piston to thereby control the pressure of air in said chamber in accordance with the speed of the vehicle, means controlled by track conditions for modifying the pressure conditions in said chamber, and means operated by the pressure in said chamber for controlling the speed of the train, substantially as described.

19. Train control apparatus, comprising an air chamber, a train-driven speedometer element working in said chamber, to affect the pressure therein, a sectional track, track apparatus, and means controlled by the track apparatus for controlling the flow of air into and the pressure in said chamber, substantially as described.

20. Train control apparatus, comprising a pressure chamber, a speed-controlling device operated by the pressure in said chamber, and means for controlling the pressure in said chamber, said means being controlled in part by the actual speed of the train at the moment, and in part by the distance which the train has traveled beyond a predetermined point in the track under predetermined track conditions, substantially as described.

21. Train control apparatus, comprising a pressure chamber, a speed-controlling device operated by the pressure in said chamber, and means for controlling the pressure in said chamber, said means being controlled in part by the actual speed of the train at the moment, and in part by the distance which the train has traveled beyond a predetermined point in the track under predetermined track conditions, together with means for preventing the operation of the

speed-controlling device when the speed of the train is below a predetermined maximum, substantially as described.

22. Train control apparatus, comprising a pressure chamber, a speed-controlling device operated by the pressure in said chamber, and means for controlling the pressure in said chamber, said means being controlled in part by the actual speed of the train at the moment, and in part by the position of the train with respect to a predetermined point

in the track under predetermined track conditions, together with means for automatically decreasing the pressure in said chamber upon reverse movement of the train, substantially as described. 15
